W. B. COGGER.

DOOR HANGER.

No. 253,471.

Patented Feb. 7, 1882.

Fig. 1.

A diagram of a hexagonal frame with a central letter 'a'. The hexagon is defined by a thick black border. Inside, there are four small circles at the vertices and a central letter 'a'. Dashed lines connect the centers of the circles to the center of the letter 'a'.

UNITED STATES PATENT OFFICE.

WILLIAM B. COGGER, OF MINNEAPOLIS, MINNESOTA, ASSIGNOR OF ONE-HALF TO HENRY A. HAMLIN, OF SAME PLACE.

DOOR-HANGER.

SPECIFICATION forming part of Letters Patent No. 253,471, dated February 7, 1882.

Application filed November 22, 1881. (Model.)

To all whom it may concern:

Be it known that I, WILLIAM BROWN COGGER, of Minneapolis, in the county of Hennepin, and in the State of Minnesota, have invented certain new and useful Improvements in Door-Hangers; and I do hereby declare that the following is a full, clear, and exact description thereof, reference being had to the accompanying drawings, and to the letters of reference marked thereon, making a part of this specification.

This invention relates to certain improvements in door-hangers; and it has for its objects to provide a device whereby the wheel or roller upon which the door travels may be confined to the track and protected from the weather, as more fully hereinafter specified. These objects I attain by the devices illustrated in the accompanying drawings, in which—

20 Figure 1 represents a view, partly in longitudinal section and partly in elevation, of my improvement. Fig. 2 represents a vertical transverse sectional view of the same, and Fig. 3 represents an end elevation of the apparatus.

25 The letter A indicates the beam, which extends across the top of the gateway and is supported by the posts at each side.

The letter B indicates an angle-rail extending longitudinally along the top of the beam 30 A, upon which the grooved roller C is adapted to travel.

The letter D indicates a block of wood longitudinally grooved, as indicated by the letter E, on the lower side, and secured by means of 35 screws F, or otherwise, to a hanger, G. The

lower edges of said block have attached to them a metallic frame, H, which extends upward and embraces the ends of the block, as indicated. The upper part of the grooved roller C is adapted to set into the groove E of 40 the block D, the frame H, at the lower edges of the block, resting upon the axle of the roller in such manner as to travel back and forth thereon, to a certain extent, as the roller travels back and forth upon the track. The frame H, 45 at its ends, is provided with downwardly-extending projections K, which prevent the block from running off of the roller.

In mounting the gate two rollers, with their attachments, are employed, one at each end of 50 the gate, the gate being secured to the hangers in any suitable manner.

Having thus described my invention, what I claim, and desire to secure by Letters Patent, is—

55 In combination with the longitudinally-grooved block D, the grooved metallic frame H, having a flat bearing-surface on its lower side for the journals of a friction-roller, and abutments at each end, the friction-roller C, 60 grooved on its periphery, and the rail B and support A, substantially as and for the purposes specified.

In testimony whereof I affix my signature, in presence of two witnesses, this 1st day of November, 1881.

W. B. COGGER.
